(57) **CLAIM**

The ornamental design for a directional sign, as shown and described.

DESCRIPTION

FIG. 1 is a front elevation view of a first embodiment of the directional sign, where the reverse side is a mirror image; FIG. 2 is a left side elevation view of a first embodiment of the directional sign;

FIG. 3 is a top plan view of a first embodiment of the directional sign;

FIG. 4 is a right side elevation view of a first embodiment of the directional sign;

FIG. 5 is a bottom plan view of a first embodiment of the directional sign;

FIG. 6 is a front elevation view of a second embodiment of the directional sign, where the reverse side is identical;

FIG. 7 is a left side elevation view of a second embodiment of the directional sign;

FIG. 8 is a top plan view of a second embodiment of the directional sign;

FIG. 9 is a right side elevation view of a second embodiment of the directional sign; and,

FIG. 10 is a bottom plan view of a second embodiment of the directional sign.

The broken lines illustrate portions of the article that form no part of the claimed design.
